UNITED STATES PATENT OFFICE

LOUIS D. GIBSON, OF NORWAY, MAINE, ASSIGNOR TO THE W. F. TUBBS COMPANY, OF NORWAY, MAINE, AN ORGANIZATION OF MAINE

DESIGN FOR A FOOT REST

Application filed July 3, 1931. Serial No. 40,413. Term of patent 7 years.

To all whom it may concern:

Be it known that I, LOUIS D. GIBSON, a citizen of the United States, and residing at Norway, in the county of Oxford and State of Maine, have invented new, original, and ornamental Design for Foot Rests, of which the following is a specification, reference being had to the accompanying drawings, forming a part thereof, in which Figure 1 is

a perspective view of a foot rest showing my new design, and Fig. 2 is a fragmentary enlarged view of the hide stringing of Fig. 1.

I claim:—

The ornamental design for a foot rest as shown.

In testimony whereof, I hereunto affix my signature this 23rd day of June, 1931.

LOUIS D. GIBSON.
